Genus and species: *Pelargonium zonale*.

Variety denomination: 'KLEPZ16424'.

CROSS REFERENCE TO RELATED
APPLICATION

The present application claims priority to Switzerland Plant Variety Protection Application No. 16-3070, as filed on Jun. 16, 2016, the entire contents are herein incorporated by reference for all the application teaches and discloses.

BACKGROUND OF THE NEW PLANT

The present invention comprises a new and distinct variety of *pelargonium*, botanically known as *Pelargonium zonale* and hereinafter referred to by the variety name 'KLEPZ16424'. 'KLEPZ16424' originated from a cross-combination in September 2010 in Stuttgart, Germany between the female *pelargonium* variety 'KLEPZ05129', also known as SUNRISE Mandarin (U.S. Plant Pat. No. 18,621) and the proprietary male *pelargonium* variety SUNRISE Racing (unpatented).

Seeds from the cross-combination were obtained and sown and plants were grown for evaluation. A single plant was selected in June 2011 and subsequently named 'KLEPZ16424'. In August 2011 'KLEPZ16424' was first vegetatively propagated in Stuttgart, Germany by vegetative cuttings from branches. 'KLEPZ16424' was found to reproduce true to type in successive generations of asexual propagation via vegetative cuttings in Stuttgart, Germany.

SUMMARY

The following are the most outstanding and distinguishing characteristics of this new variety when grown under normal horticultural practices in Stuttgart, Germany.

1. Large salmon-orange colored flowers with re-purple eyes; and
2. An upright growth habit.

DESCRIPTION OF THE PHOTOGRAPH

This new *pelargonium* plant is illustrated by the accompanying photograph which shows an overall view of the plant. The photograph is of an approximately nine to ten-week-old plant grown in Stuttgart, Germany under greenhouse conditions in May 2015. The colors shown are as true as can be reasonably obtained by conventional photographic procedures.

DESCRIPTION OF THE NEW VARIETY

The following detailed descriptions set forth the distinctive characteristics of 'KLEPZ16424'. The data which define these characteristics were collected from asexual reproductions carried out in Stuttgart, Germany. Data was collected on plants grown three months after planting in Stuttgart, Germany under a glass covered greenhouse in April 2017. Color references are to The R.H.S. Colour Chart of The Royal Horticultural Society of London (R.H.S.), 5th edition (2007).
